UNITED STATES PATENT OFFICE.

JOSEPH K. SIERER, OF NEW YORK, N. Y.

DESIGN FOR A TILE.

SPECIFICATION forming part of Design No. 85,436, dated December 10, 1901.

Application filed November 16, 1901. Serial No. 82,596. Term of patent 14 years.

To all whom it may concern:

Be it known that I, JOSEPH K. SIERER, a citizen of the United States, residing at New York, in the county and State of New York, have invented and produced a new and original Design for Tiles, of which the following is a specification, reference being had to the accompanying drawings, forming a part thereof.

In the accompanying drawings, Figure 1 is a plan view of a tile, showing my design; and Fig. 2 is a perspective view of said tile.

As shown in the drawings, the leading or material features of my invention consist of tongues A and A' and recesses B and B', shaped and disposed or arranged substantially as shown in the drawings. The tongues A are of a right-angled hook shape, while the recesses B are of an exactly similar shape. The tongues A' are somewhat of a hook shape, 20 the shape differing slightly from that of the

tongues A, said tongues A' being each provided with a beveled edge A², as shown. The recesses B' are shaped exactly similar to the tongues A'. The tongues A and recesses B are disposed upon two opposite sides of the tile, while the tongues A' and the recesses B' are disposed upon the remaining two sides of the tile.

Having described my invention, what I claim as new, and desire to secure by Letters Patent, is—

The design for a tile, as herein shown and described.

In witness whereof I have hereunto signed my name in the presence of the subscribing witnesses.

JOSEPH K. SIERER.
